UNITED STATES PATENT OFFICE.

JOSEF VAN HÜLLEN, OF CREFELD, GERMANY.

MOLD BOX FOR BLOCK PRESSES.

Application filed October 17, 1924. Serial No. 744,192.

To all whom it may concern:

Be it known that I, JOSEF VAN HÜLLEN, a citizen of the German Republic, residing at Crefeld, Germany, have invented certain new and useful Improvements in Mold Boxes for Block Presses, of which the following is a specification.

This invention relates to a mold for celluloid block presses. In order to facilitate the ejection of the celluloid blocks which after the pressing adhere strongly to the mold walls, or in order to effect this ejecting with less pressure than usually the pressing faces are formed, according to the invention, of conical plates which bear during the pressing against the also conical inner walls of the mold and form a pressing space of plane faces. These heatable plates rest during the pressing with their lower edges on shoulders of the mold faces and at the ejecting of the pressed blocks they are lifted together with said blocks by the adhesion action until their projections butt against abutments of the molds. Owing to the conical shape of the pressing plates a free space is formed at the raising of said plates between said plates and the walls of the mold so that, after having arrived at their extreme position, they can give way in lateral direction and drop back into the initial position, the released celluloid block being then completely removed from the mold. This arrangement presents an advantage in so far as only the comparatively thin plates need be heated, while in the commonly used constructions, the considerably thicker walls of the mold have to be heated. The mold box used may be in one part or composed of several parts.

An embodiment of the invention is shown on the accompanying drawing in which a mold box composed of four parts is shown by way of example.

Fig. 1 is a plan view of the mold top of a block press.

Fig. 2 is a section on line A—A, and Fig. 3 is a section on line B—B of Fig. 1.

The mold box of the block press is composed of four walls *a*, *b*, *c*, *d* held together by screw bolts *e*. The inner edges of the ribs *f* extend feebly conically. The conical plates *g* bear against these edges so that the inner space formed by the same is enclosed by vertical faces. The plates *g* are connected with one another at the edges by tongue-

and-groove connection and they have inner channels *i* for the heating medium. The lower edges of the plates *g* rest normally on shoulders *k* of the walls of the mold box. The plates *g* have projections *m* on the outer faces.

If after the pressing the compressed material is ejected in the direction of the arrow *I* the plates *g* are lifted also owing to the adhesion which exists between them and the compressed material, until the projections *m* strike against the abutments *n* in the walls of the mold box. Between the walls of the mold box and the plates *g* a free space is formed owing to the conical shape of the plates so that after the plates have arrived at their extreme position they can give way in lateral direction and drop back onto the shoulders *k*. The compressed material is then ejected without any lateral friction.

I claim:—

1. A mold box for block presses comprising in combination with the box proper having conical inner walls, conical heatable plates bearing against said conical inner walls of the mold box so that an inner space is formed enclosed by vertical faces, projections on said conical plates, and abutments on the inner walls of the mold box for limiting the movability of said heatable plates.

2. A mold box for block presses comprising in combination with the box proper having conical inner walls, conical heatable plates bearing against said conical inner walls of the mold box so that an inner space is formed enclosed by vertical faces, groove-and-tongue connections between the adjacent edges of said heatable plates, projections on said conical plates, and abutments on the inner walls of the mold box for limiting the movability of said heatable plates.

3. A mold box for block presses comprising in combination with the box proper having conical inner walls, shoulders on the inner walls of said mold box, conical heatable plates bearing against said conical inner walls of the mold box so that an inner space is formed enclosed by vertical faces, the lower edges of said plates resting normally on said shoulders of the mold box, projections on said conical plates, and abutments on the inner walls of the mold box for limiting the movability of said heatable plates.

4. A mold box for block presses comprising

ing in combination with the box proper walls of the mold box for limiting the mova-
having conical inner walls, conical heatable bility of said heatable plates. 10
plates bearing against said conical inner plates
walls of the mold box so that an inner space
is formed enclosed by vertical faces and
having inner channels for the passage of
the heating medium, projections on said
conical plates, and abutments on the inner

In testimony whereof I affix my signature
in presence of a witness.

JOSEF VAN HÜLLEN
